US00D740999S

(12) **United States Design Patent**
Yu

(10) **Patent No.:** **US D740,999 S**
(45) **Date of Patent:** **** Oct. 13, 2015**

(54) **LIGHTHEAD LENS**

(71) Applicant: **Ningbo Yinzhou Self Photoelectron Technology Co., Ltd.**, Ningbo, Zhejiang (CN)

(72) Inventor: **Feng Yu**, Ningbo (CN)

(73) Assignee: **NINGBO YINZHOU SELF PHOTOELECTRON TECHNOLOGY CO., LTD.**, Ningbo (CN)

(**) Term: **14 Years**

(21) Appl. No.: **29/502,126**

(22) Filed: **Sep. 11, 2014**

(30) **Foreign Application Priority Data**

May 16, 2014 (CN) 2014 3 0134997

(51) **LOC (10) Cl.** **26-99**

(52) **U.S. Cl.**

USPC **D26/120**; D26/28

(58) **Field of Classification Search**

USPC D26/9, 10, 12, 13, 15, 16, 24, 51, 61, D26/72, 76, 80, 81, 85, 86, 88, 90, 113, 118, D26/119, 120, 122, 128, 129, 138, 143, 144, D26/5, 6, 11, 79, 114, 116, 131, 137, 121, D26/127, 135, 180, 28; D13/180; D10/18, D10/21, 24, 25, 27, 28, 46, 93, 104.1, 113, D10/114, 116.1; D17/99

Primary Examiner — Kevin Rudzinski

Assistant Examiner — Sean D Lough

(57) **CLAIM**

The ornamental design for a lighthead lens, as shown and described.

DESCRIPTION

FIG. 1 is a front elevational view of a lighthead lens showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a first perspective view thereof;

FIG. 8 is a second perspective view thereof; and,

FIG. 9 is a third perspective view thereof.

1 Claim, 8 Drawing Sheets
